R. S. BOLGER

LAMINATED SPOOL

Filed Nov. 6, 1920

Inventor
Robert S. Bolger
By his Attorneys
Meyers, Cavanagh Hyde

UNITED STATES PATENT OFFICE.

ROBERT S. BOLGER, OF NEW YORK, N. Y.

LAMINATED SPOOL.

Application filed November 6, 1920. Serial No. 423,370.

To all whom it may concern:

Be it known that I, ROBERT S. BOLGER, a citizen of the United States, and resident of New York city, in the county of Queens and State of New York, have invented certain new and useful Improvements in Laminated Spools, of which the following is a specification.

My invention relates to improvements in the manufacture of spools, cops and similar articles of the type which is formed of sheet material arranged in superposed layers.

In order to avoid the excessive waste and various technical and commercial difficulties involved in the manufacture from wooden stock of the various forms of spools, cops, bobbins and the like, hereinafter generally referred to as spools, it has heretofore been proposed to form such spools from flexible sheet material, such as paper or the like, arranged in adhesively connected circumaxial layers about the usual central bore. The product so formed has been found to possess inherent advantages over the wooden spool aside from convenience of manufacture, such as smoothness and regularity of surface, freedom from the tendency to crack and split, and resistance to moisture.

In manufacturing spools of this type, however, it has heretofore been the universal practice so far as I am aware to employ a blank or blanks so formed and proportioned that when treated with glue and rolled up, a spool of the desired contour is produced. The manufacture of spools by this method involves various problems relating to the handling of blanks of various irregular shapes, and to the devising of mechanism for rolling such blanks into form. These problems present substantial difficulty in the designing of a suitable machine, particularly when high quantity production and a minimum of defective spools is required.

An important object of my invention is to provide a method of manufacturing laminated spools from sheet material which will eliminate the problems incident to handling the type of blank heretofore employed. In a general way, I accomplish this object by constructing a cylinder from sheet material in any of the various well-known ways, and then forming a spool or spools from the cylinder by removing suitable portions thereof.

Another object of my invention is to produce a plurality of spools from a single blank. I accomplish this object by employing a cylinder of substantial length, from which a plurality of spools may be manufactured, with but a single rolling and gluing operation to produce the cylinder.

A principal advantage of this general method resides in the fact that machines for manufacturing cylinders from sheet material, particularly from paper pasteboard and the like, are well known and thoroughly developed; and such cylinders may be produced very rapidly and cheaply by standard machinery. Furthermore, mechanism for forming the cylinder into spools may be of very simple, rapid-acting and efficient construction.

In constructing spools from sheet material by the methods heretofore known and above outlined, the blanks were necessarily wound substantially at right angles to the spools axis. This necessarily resulted in ridges at the points where the beginning and end of the blank overlay the adjacent lamination. The only known way to avoid such ridges is to wind the sheet helically about the axis at such an angle that adjacent edges of the sheet will abut; but this construction necessitates a separate sheet for each lamination, which is obviously impractical with the former method of construction.

Another object of my invention is to provide a spool made from sheet material, which is free from the terminal ridges of the earlier construction; and a particular object is to accomplish this result by forming a spool from helically wound sheet material. Spools of this type would be impractical to manufacture separately, but are very conveniently manufactured by my improved method above indicated, in which the cylinder may first be manufactured from helically wound sheets, the spools being thereafter formed from the completed cylinder.

Another object of my invention, which is collateral to those just mentioned, is to provide a continuous process for manufacturing laminated spools from sheet material. A process in which the blank is rolled at right angles to the axis is almost necessarily discontinuous, since the blanks must be severed across the direction of blank supply. Where, however, a cylinder is first constructed by

helical winding, and then formed into spools, the cylinder manufacture can be continuous and the spools may be made and cut off from the cylinder as it is formed.

5 Other objects and advantages of my improved construction will be apparent from the following description, taken in connection with the accompanying drawings, in which:

10 Fig. 1 is a plan view of an end portion of a laminated cylinder, showing several spools in course of construction and indicating mechanism for forming and severing the spools, the parts being shown in spool-forming position,

15 Fig. 2 is a view similar to Fig. 1, parts being shown in spool-severing position,

20 Fig. 3 is a plan view of a spiral-wound cylinder, parts being broken away, with a formed and severed spool shown at the end of the cylinder, the portions to be cut away in forming successive spools being indicated by dot-and-dash lines,

25 Fig. 4 is a transverse section along lines 4—4 of Fig. 1,

Fig. 5 is a side elevation of a straight-wound spool,

30 Fig. 6 is a side elevation of a helical-wound spool,

35 Fig. 7 is an end view of a straight-wound spool, and

Fig. 8 is an end elevation of a helical-wound spool.

In practicing my improved method, I first 35 construct a cylinder 10 of suitable thickness, having an outside diameter at least equal to the diameter of the largest spool to be formed, from suitable sheet material such as paper, cardboard or other substances 40 which possess sufficient flexibility and hardness to serve the purpose. The cylinder 10 may be of any desired length, equal to or greater than the length of the finished spool; but in the preferred form I employ a cylinder 45 many times the length of a single spool, so that a large number of spools may be formed from a single cylinder.

Various methods of constructing the cylinder may be employed, as is well known to 50 those skilled in the art, either the direct rolling method illustrated in the cylinder of Fig. 1, or the helical method shown best in Fig. 3, being adapted for my purpose; though my invention obviously is not restricted to these two specific methods of 55 constructing the cylinder. The superposed laminations of the cylinder are firmly connected to each other by adhesive to form a coherent structure, so that the laminations 60 of the finished spool will not tend to separate.

I next form the spool from the cylinder by cutting away portions of the cylinder surface to produce the desired shape. Various 65 methods of cutting may be employed,

the preferred form indicated in the drawings including the employment of grinding wheels suitably contoured to cut into the face of the cylinder. The excising process may be completed in one step by employing 70 a single cutter of the desired form; but to produce a well-finished product and increase the capacity of the machine, successive cutters may be employed, as in Fig. 1, it being understood that the cylinder is 75 shifted to the right into engagement with successive cutters 11 and 12. In the form shown, these cutters are proper shaped grinding wheels of the well-known type.

After the cylinder surface has been properly cut away, and where the cylinder is of a length greater than that of a single spool, the finished spool adjacent the end of the cylinder is cut off, the construction shown in Fig. 1 including a saw 13 movable relative 80 to the cylinder and so located that it will cut accurately between adjacent spools. For the purpose of supporting the cylinder against the lateral thrust of the grinding and cutting mechanism, I may employ a 85 suitable mandrel 14 extending into the end of the cylinder, the remainder of the cylinder being supported in any desired way.

One problem connected with the shaping and severing of laminated cylinders of paper or similar material is the fact that rotating cutting or abrading means would tend to strip the successive laminations from each other, unless the direction of rotation of said means is such that its contact with 100 the cylinder will be in the direction of winding of the laminations. This problem does not arise in wood-turning, but is particularly important in producing a finished product of the type disclosed herein. 105

In the form shown in Fig. 1, the cylinder has been wound in a clockwise direction viewed from the left end of the figure. The grinding wheels 11 and 12 and the saw 13 therefore also rotate in a clockwise direction viewed from the same point. To provide uniform action on all sides of the cylinder, the latter may be moved in a clockwise direction as indicated by the arrow at the left, or in the opposite direction, provided the speed of the cutting mechanism is substantially greater than that of the cylinder 115 so that the movements between the cylinder and cutting mechanism will be in the direction of cylinder formation. 120

In the specific construction disclosed, I have provided for a cylinder of considerable length which is fed step by step to the right into engagement with spool-forming units, the completed spool being severed from the 125 right-hand end of the cylinder. I wish it understood that my invention is not necessarily limited to this method of construction, as a great many variations in the precise methods used, and particularly various 130

methods of gang manufacture or of individual spool manufacture, may obviously be substituted within the range of my broad idea. However, the particular method 5 shown is especially advantageous in connection with machines for producing helical-wound cylinders of the type shown in Figs. 3, 6 and 8, which manufacture the cylinder continuously and feed it to the right from 10 the machine. This permits continuous formation and separation of spools from the cylinder without arresting the operation of the apparatus to insert new cylinders.

The spool produced by my improved process, shown best in Figures 4 to 8 inclusive, 15 may obviously have any desired contour, this being determined by the shape of the cutting elements 11 and 12. The spool shown is of the ordinary type used for 20 thread, including the central barrel 15 and the end flanges 16. In the form shown in Figs. 4, 5 and 7, which are made from a straight-wound cylinder, it will be apparent 25 that the entire spool is formed from a single blank of sheet material, while in the spool of Figs. 6 and 8, both the barrel 15 and the flanges 16 are composed of a number of superposed, adhesively connected portions of sheet material. Regardless of 30 whether the spool is made of one or of many separate sheet portions, however, the spool has substantially the same characteristics, and is readily manufactured from practically any type of laminated cylinder.

35 While I have described the preferred forms of my invention and indicated certain variations therein, it will be apparent that many other changes may be made without departing from the spirit of my invention. 40 For instance, a large number of changes in the method of manufacture are possible, as well as in the finished contour of the spool, depending upon the method of manufacture used and the type of spool which is desired.

45 I claim:

1. The method of manufacturing laminated spools which consists in winding sheet material helically to form a laminated cylinder having a plurality of spirally wound layers of an aggregative thickness sufficient for 50 forming the body of a spool, in excising portions of said cylinder so formed to provide a spool formation with its central barrel and end flange portions and in severing the spool formation from the said cylinder. 55

2. The method of manufacturing laminated spools which consists in winding sheet material helically to form a laminated cylinder having a plurality of spirally wound layers of an aggregative thickness sufficient for 60 forming the body of a spool, adhesively connecting said layers, in excising portions of said cylinder so formed to provide a spool formation with its central barrel and end flange portions and in severing the spool formation 65 from the said cylinder.

3. The method of manufacturing laminated spools which consists in winding sheet material helically to form a continuous laminated cylinder having a plurality of spirally wound layers of an aggregative thickness sufficient for forming the body of the spool, in excising successive zones of said cylinder so formed to provide spool formations 70 each with its central barrel and end 75 flanges and severing the spool formations from the said cylinder.

4. A laminated spool made of sheet material and composed of sheet layers wound in helical formation and providing a barrel and 80 end flanges having spirally wound laminations.

5. A laminated spool made by winding sheet material helically along an axis and comprising a barrel and end flanges having 85 spirally wound laminations.

Signed at New York city in the county of New York and State of New York this 22nd day of October, A. D. 1920.

ROBERT S. BOLGER.
